PACKAGE LIFTING TONGS

Joseph F. Baribault, New Haven, Conn.

Application December 23, 1947, Serial No. 793,436

3 Claims. (Cl. 294—22)

1

The present invention relates in general to lifting devices and more especially to tongs for handing down packages, bottles, and similar articles stored on high shelves or other elevated places beyond the reach of an ordinary person.

An object of the invention is to provide superior tongs characterized by relatively-simple and durable construction and embodying a minimum number of elements adapted to be assembled in cooperative relationship without recourse to machining, screw-threading, and similar relatively-expensive manufacturing operations.

A further object of the invention is to provide superior tongs having gripping-elements sheathed in resilient sleeves and a tubular shaft provided at its lower end with an operating-handle designed to provide a smooth streamlined construction devoid of lateral projections and circumferential enlargements.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a front elevation of the improved package-lifting tongs of this invention;

Fig. 2 is a top plan view of the tongs of Fig. 1 showing the jaws in their closed position;

Fig. 3 is a fragmentary elevation of the lower end of the tongs, including the operating-handle on section-line 3—3 of Fig. 1;

Fig. 4 is an end elevation on section-line 4—4 of Fig. 1; and

Fig. 5 is an end elevation on section-line 5—5 of Fig. 1.

An exemplary embodiment of the invention is shown in the drawings, in which the shaft of the tongs is designated at 10 and comprises a metal tube, preferably aluminum or similar lightweight material, of substantially-uniform internal and external diameters and of a length suitable for the purposes for which the tongs are designed. The gripping-elements of the tongs are indicated at 11 and 12 respectively and consist of relatively-stiff pieces of wire or rod, each comprising a shank-portion 13 and 14 respectively and a jaw 15 and 16 respectively. Each jaw is bent at substantially right angles to its respective shank-portion and is arcuate in shape, as shown especially well in Fig. 2, the curvature of each arcuate jaw being such that it bows outwardly laterally and then inwardly to form article-en-

2

circling arms adapted to close around a can or similar cylindrical object, the outer inwardly-directed portions 17 and 18 respectively of the jaws serving to cam an article inwardly toward the inner ends thereof. The outer extremity of each jaw is provided with a forwardly-projecting straight section 19 and 20 respectively to facilitate lifting articles of rectilinear shape. Moreover, the jaws are adapted to lie in a common plane at substantially right angles to the longitudinal axis of the shaft 10. In the preferred construction, each jaw is provided with a resilient anti-slip sleeve 21 and 22 respectively which comprises a short length of rubber tubing fitted tightly thereover. It will be understood, however, that any other suitable anti-slip material may be used.

The gripping-elements 11 and 12 are adapted to be mounted in the upper end of the shaft 10 and to this end, two substantially-diametrically-opposite indentations or creases 23 and 24 are formed in the latter, each of which extends substantially longitudinally from the open upper end of the shaft downwardly for a length corresponding substantially to the length of the shank-portions of the gripping-elements 11 and 12, thereby to form a pair of spaced-parallel substantially-cylindrical restrictions 25 and 26 in the upper end of the shaft for supporting the shanks 13 and 14 of the respective jaws, as indicated clearly in Figs. 4 and 5. The gripping-element 11 is adapted to be fixedly secured to the upper end of the shaft, and to this end its shank 13 is fastened in its respective restriction 25 by fastening-means comprising a pin or rivet 27 extended transversely through the cylindrical restriction 25 and the shank 13 of the gripping-element 11. The gripping-element 12 is adapted to be pivotally mounted in the upper end of the shaft so as to be movable into and from cooperative relationship with the fixed gripping-element 11, and to this end its shank 14 is rotatable in its cylindrical restriction or bearing 26, and is formed with an integral reach 28 which extends downwardly freely in the tubular shaft beyond the lower end thereof where it is adapted to be secured to the operating-handle of the tongs, as hereinafter described. Since the shank 14 is movable freely in its cylindrical bearing 26 and since it is necessary for satisfactory operation that the jaw 12 remain in substantially the plane of the corresponding jaw 11, suitable means is provided to prevent the shank 14 from moving longitudinally in its bearing. Referring especially to Figs. 1 and 3, the substantially-right-

angle bend 29 which the jaw 16 makes with its shank-portion immediately above the upper end of its bearing 26, constitutes stop-means to prevent the shank 14 from moving downwardly therein. The shank is prevented from moving upwardly in its bearing by fastening the lower end of its reach 28 to the operating-handle which is mounted on the lower end of the shaft and held from moving upwardly thereon by suitable stop-means hereinafter described.

The operating-handle is indicated at 30 and comprises a tubular member or sleeve, the upper portion 31 of which is of substantially-uniform external diameter and has an internal diameter substantially equal to the external diameter of the lower end of the shaft 10 so as to make a relatively-snug-but-freely-rotatable fit thereon. The lower portion 32 of its length extends downwardly below the lower end of the shaft 10 and is adapted to form the handgrip area thereof, and to this end is pinched together along two diametrically-opposite longitudinally-extending indentations 33 and 34 respectively to form a pair of substantially-cylindrical restrictions, one of which, as indicated at 35, is adapted to receive the lower end of the reach 28. A rivet 36 or equivalent fastening-means is provided which extends transversely through the restriction 35 and the lower end of the reach for securing the two together.

Referring especially to Fig. 3, it will be clear that in forming the diametrically-opposite longitudinal indentations 33 and 34 in opposite sides respectively of the sleeve-like operating-handle 30 below the lower end of the shaft 10, the inner walls of this portion of the handle converge and the indentations, in particular, form shoulders 37 and 38 respectively, hereinafter referred to as "stop-means," immediately below the lower end of the shaft 10. These shoulders effectively prevent the handle from being moved upwardly longitudinally on the shaft, and inasmuch as the reach 28 of the second jaw is fastened to the operating-handle by the aforementioned rivet 36, the reach and its jaw 16 are similarly held from moving upwardly longitudinally within the shaft.

It will be appreciated that the tongs are adapted to be operated by grasping the shaft 10 in one hand intermediate its opposite ends and the operating-handle 30 in the other hand, and turning the latter on the shaft, whereupon the pivotal jaw 16 is adapted to swing into and from cooperative engagement with the fixed jaw 15 for engaging and lifting packages, jars, and the like, from a high shelf.

The tongs are of unusually simple construction embodying the five principal elements, all of which are readily obtainable and adapted for quick assembly without requiring expensive machining operations or assembling-jigs. Moreover, the tongs are extremely simple to operate, have a smooth streamlined construction of pleasing appearance, and free from lateral projections or other obstructions and disfigurements.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. Tongs of the class described, comprising:

tubular shaft having a pair of restrictions formed in the upper end thereof; a jaw fixedly secured in one restriction; a second jaw rotatably mounted in the second restriction, the second jaw having a reach extending downwardly to the lower end of said shaft; operating-means for moving said second jaw into and from cooperative relationship with said fixed jaw comprising a sleeve rotatably mounted on the lower end of said shaft, and an element arranged to secure said sleeve to the lower end of said reach; and stop-means comprising a shoulder on said reach arranged to cooperatively engage the said second restriction to hold the rotatable jaw from moving downwardly in said shaft and a shoulder on said sleeve arranged to cooperatively engage the lower end of said shaft to hold the rotatable jaw from moving upwardly in said shaft.

2. Tongs of the class described, comprising a tubular shaft having longitudinal substantially-diametrically-opposite indentations in the upper end thereof to divide the latter into two separate substantially-cylindrical restrictions; a jaw having a shank-portion arranged to engage in one of the said cylindrical restrictions; fastening-means to secure said shank in said cylindrical restriction; a second jaw having a shank-portion rotatably mounted in said second restriction and a reach integral with said shank-portion, said reach extending downwardly freely within said shaft to the lower end thereof; operating-means for moving said second jaw into and from cooperative relationship with said fixed jaw comprising a uniformly-cylindrical sleeve rotatably mounted on the lower end of said shaft, said sleeve having a cylindrical restriction arranged to receive the lower end of said reach and fastening-means to secure the lower end of said reach in the cylindrical restriction of said sleeve; and stop-means to hold said second jaw from moving longitudinally with respect to said shaft comprising a stop-shoulder on the upper end of the said shank-portion of said rotatable jaw arranged to cooperatively engage with the upper end respectively of the said second cylindrical restriction to hold the rotatable jaw from moving downwardly in said shaft and a stop-shoulder at the upper end of the cylindrical restriction of said sleeve arranged to cooperatively engage with the lower end of said shaft to hold said sleeve from moving upwardly thereon.

3. Tongs of the class described, comprising a tubular shaft having longitudinal substantially-diametrically-opposite indentations in the upper end thereof to divide the latter into two separate substantially-cylindrical restrictions; a jaw comprising an arcuate-portion having a substantially-straight terminal-portion and a shank-portion, said shank-portion being arranged to engage in one of the said cylindrical restrictions; fastening-means to secure said shank in said cylindrical restrictions; a second jaw comprising an arcuate-portion having a substantially-straight terminal-portion and a shank-portion, said shank-portion being rotatably mounted in said second restriction and provided with a reach integral therewith, said reach extending downwardly freely within said shaft to the lower end thereof; operating-means for moving said second jaw into and from cooperative relationship with said fixed jaw comprising a uniformly-cylindrical sleeve rotatably mounted on the lower end of said shaft, said sleeve having a cylindrical restriction arranged to receive the lower end of said reach, and fastening-means to secure the lower end of

said reach in the cylindrical restriction of said sleeve; stop-means to hold said second jaw from moving longitudinally with respect to said shaft comprising a stop-shoulder on the upper and lower ends respectively of the said shank-portion of said rotatable jaw arranged to cooperatively engage with the upper and lower ends respectively of the said second cylindrical restriction to hold the rotatable jaw from moving downwardly in said shaft and a stop-shoulder at the upper end of the cylindrical restriction of said sleeve arranged to cooperatively engage with the lower end of said shaft to hold said sleeve from

moving upwardly thereon; and a resilient anti-slip sleeve on each of said first and second jaws.
